UNITED STATES PATENT OFFICE.

HERBERT L. AULLS, OF DENVER, COLORADO.

CONVERTIBLE DUMPING-CAR.

No. 850,719.

Specification of Letters Patent.

Patented April 16, 1907.

Application filed January 9, 1907. Serial No. 351,559.

To all whom it may concern:

Be it known that I, HERBERT L. AULLS, a citizen of the United States, and a resident of Denver, county of Denver, State of Colorado, have invented certain new and useful Improvements in Convertible Dumping-Cars, of which the following is a specification.

My invention relates to convertible dumping-cars, and especially car-platforms used as the bottoms of coal and ore cars, although it will be understood that my invention can be used as the bottom of bins, storage-elevators, and like structures.

The main object of my invention is to provide a car with a floor which can be transformed into a perfectly flat surface, such as the floor of a "gondola" car, or which can be arranged so that the contents can be discharged inwardly underneath the car or to either side of the car from the middle of the car without shoveling or without the use of a plow, as heretofore required in most cars of this type.

A further object of the invention is to utilize such a construction for bins and storage structures whether mounted upon wheels or in fixed positions.

The desideratum in a dumping-car is that the load may be discharged at will either to one side or the other or inwardly underneath the car and that the bottom of such a car may be made perfectly flat.

In the accompanying drawings I have illustrated my invention as applied to a car.

Figure 1 is a transverse sectional view of a car illustrating my invention. Fig. 2 represents a longitudinal side view of a car provided with my improved dumping-platform. Fig. 3 is a plan view of the same, taken when the hopper-bottom floor is closed and locked ready for loading. Fig. 4 is a section taken on the line *s-s* when the car is discharging outwardly. Fig. 5 is a section on the line *s-s* when the car is discharging inwardly. Fig. 6 is a section on the line *s-s* when the car is changed to flat bottom. Fig. 7 is a section taken on the line *r-r* when the car is discharging outwardly. Fig. 8 is a section taken on the line *r-r* when the car is discharging inwardly. Fig. 9 is a section taken on the line *r-r* when the car is changed to flat bottom. Fig. 10 is a transverse section of a car having additional side doors, and Figs. 11 and 12 are transverse sections of a car having modified forms of floors.

It will be noticed in the drawings that the

car-body has the ordinary sides and a longitudinal fixed member *P* extending from one end of the car to the other. This fixed member may be in the form of a beam or a series of beams, according to the width of the car, as desired. There are two sets of doors or sides between this central longitudinal member and the sides of the car, one door of each set being pivoted at the side of the car and the other at the side of the longitudinal member.

While I have described the doors as being operated by longitudinal rods actuated from the ends of the car, the doors may be operated by any suitable mechanism, depending considerably upon the type of car to which the invention is applied. If my invention is applied to a bin or container, then the bottom of the bin has the longitudinal member extending throughout its length, with the two sets of doors pivoted as described and arranged near one side of the central member and the other on the opposite side. It will be seen, however, that for small cars, bins, or containers the construction may be modified by omitting the longitudinal central member and using one set of depending doors pivoted to the sides, the balanced door being used for locking and opening.

Referring to the drawings, *A A* represent rods or shafts, preferably running the entire length of the car, one at each side of the central longitudinal axis and being provided at intervals on their under sides and rigidly affixed thereto with wide projections *a* for the purpose of pressing against the under side and returning the swinging doors to position. These shafts may be turned by any suitable means, either by gearing operated by hand or compressed-air power. On each rod *A* is hinged a triangular member *T*, which is adapted to be swung up from its horizontal position to an inverted-V position on turning the rod for the purpose of providing a hopper-bottom at each side. To each shaft *A* is hinged and depending therefrom a swinging door *D*. Along each side of the car is a similar rod *B*, running, preferably, the entire length of the car and is provided with similar projections *b*, rigidly affixed thereto. To these shafts are hinged swinging doors *E*. The doors *D* and *E* form a V-shaped hopper on each side and extend practically the length of the car. Below the level of the floor and substantially over each set of wheels about midway between the rods *A* and *B* is a similar rod or shaft *C*, having a balanced door *F*,

rigidly attached thereto, forming a chute for directing the discharge of the load either to the sides of the car or between the wheels. When in horizontal position, both the doors 5 E and D are locked in position—by the balanced door F in the present instance. The doors D and E may each be made of single continuous leaves or of several leaves, according as constructive details and use of the car 10 may determine. Fig. 3 shows E in three leaves.

Referring to Figs. 4, 5, 7, and 8, it will be seen that the two triangular pieces T form an inverted-V-shaped division running nearly 15 the entire length of the car above the level of the floor. When the two triangular portions T are turned up into this position, the top portions of these triangular portions interlock by means of an L-shaped overlap w, 20 Fig. 1, in a direct line with the draw-bars of a car, thereby permitting the entire load to be discharged at once and avoiding the shoveling or "plowing" usually required in cars provided with the side discharge. It will be 25 seen from the drawings, Fig. 2, that the doors E also extend practically the entire length of the car, and when the load is discharged outwardly the inner side of the doors F are tilted upward to permit the doors E to swing out at 30 each side of the car, Fig. 4, while the doors D remain fixed in position and overlapping the inside vanes of the doors F. When the load is to be discharged between the rails, the door F is swung in the opposite direction, and 35 the doors D swing inwardly on the rods A A.

When it is desired to provide the car with a flat bottom, the swinging doors E will be raised a sufficient distance to permit the triangular piece T to revolve around the central 40 shaft A into its horizontal position, whereby the triangular member T is turned over until one of its right-angle faces becomes part of the level floor. (See Figs. 6 and 9.) The door E is then swung downwardly into its 45 horizontal position.

In the modification shown in Figs. 11 and 12 instead of having triangular pieces T, I use two doors loosely hinged to a central rod or shaft S, running the entire length of the 50 car and provided with any suitable raising and lowering means. It is readily seen, therefore, that when it is desired to provide the car with a flat bottom the side doors E' are raised above the level of the floor before 55 lowering the rod S, so that the central doors T' will lie in under the side doors E', Fig. 12.

In the modification shown in Fig. 10 an additional door G may be hinged to the side rods B, so that instead of raising the door E 60 to a level-floor position the door G may be lowered to that position. When the car is adapted to discharge, this door is held in upright position by means of the catches H on the sides of the car.

65 It will be seen by the above description

that if the sections of the bottom of the car are in the position as shown in Fig. 6, the bottom being perfectly flat, to convert it into a hopper-bottom car all that is necessary is to raise the two doors E E sufficiently to allow the triangular members F to be turned up, as indicated in Fig. 5. The two doors D D are swung in position, as well as the doors E E, and locked by the balanced doors F. When the doors are in this position, the 70 contents of the car can be discharged either from each edge, as indicated in Fig. 4, or at the center, as illustrated in Fig. 8, according to the direction in which the balanced doors F are moved. After the load has been discharged and it is desired to provide the car with a flat bottom all that is necessary is to shift the several parts to the position shown in Fig. 6.

It will be noticed by comparing Figs. 4, 5, 85 and 6 with Figs. 7, 8, and 9 that the balanced doors F have long outer vane members and short inner vane members, and their widths depend upon the extent to which they are intended to act as chutes for directing the 90 discharging material. The lengths of these vanes are the same as the depending doors which they lock, and the outer vane members extend, therefore, practically the full length of the car, permitting discharge outwardly over the trucks, while the inner vane members are restricted in length to practically the distance between trucks, so that material will not be discharged upon the trucks. The members marked D' in Figs. 3, 95 4, 5, and 6 are immovably fixed over the trucks and at the same slopes as the doors D.

In erecting my improved floor for use in a bin or other container the side openings may be connected with a chute and the central 105 opening may be connected with another chute directing the contents of the bin to different discharge-points; but my invention is particularly adapted for use in connection with cars either of the open or closed types. 110

As I stated above, I do not wish to limit myself to this construction as applied to cars, and in the following claims the term "car" may be considered as applying to a bin, storage-elevator, or the like wherein my 115 convertible dumping-platform may be used; nor do I wish to limit myself to the construction as applied to full-size dumping-cars, for it is obvious that the idea of a balanced door locking two inclined swinging doors and 120 directing the discharge to either side of the track may be applied to small dumping-cars for use in mines and the like which are not of sufficient width to permit two longitudinal V-shaped hoppers.

What I claim is—

1. The combination in a car or other container, the bottom of said car or container having a longitudinally-fixed portion, a pair of doors at each side of the fixed portion, one 130

door for each set being pivoted at the edge of the fixed portion and the other door of each set being pivoted at the side, and means arranged to be shifted so as to form an inverted-⁵ V-shaped rib above the central fixed portion of the floor or to form with the outer doors a level floor.

2. The combination in a car or other container, of a floor made up of a central member and two sets of hinged doors, one set at each side of the central member, one door of each set being hinged at the edge of the central member, and the other door of each set being hinged at the side of the car or other ¹⁰ container, a balanced door pivoted at a point directly under where the two doors of each set come together, with means for operating the several doors, the said balanced doors acting as a lock for both doors when in its ¹⁵ central position, and when shifted to one side or the other acting to release one or the other of the doors of each set.

3. The combination of a car having a floor composed of four longitudinally-hinged doors, ²⁰ two of said doors being hinged to the outer side of the car and one on each side of the center of the car, means for operating said doors, means for locking the doors in the positions to which they are adjusted, and means ²⁵ for forming a ridge throughout the longitudinal center of the car.

4. The combination in a car having a floor made up of a central fixed member and four hinged doors, the outer doors being hinged at ³⁰ the sides of the car and the inner doors being hinged one to each side of the fixed member, means for operating the doors so that the doors can swing on their pivots, and a pair of members between and above the inner depending doors, so arranged that the members ³⁵ can be raised to form an inverted-V-shaped longitudinal rib, or lowered to form a flat bottom for the car.

5. The combination in a car-body, of a ⁴⁰ central fixed member extending the full length of the car, a door hinged to each side of said central member and a door hinged to each side of the car, a balanced door pivoted below the pivots of the first-mentioned doors ⁴⁵ and about midway between said pivots, said doors being so arranged as to lock the doors on each side of the center when in the mid-position, and acting to release one door and lock the other when in one of its other two ⁵⁰ positions.

6. The combination in a car, of a central ⁵⁵ fixed member, two doors on each side of the said fixed member, one door of each set being hinged to said fixed member and the other door being hinged at the side of the car, a balanced door acting to lock the two doors closed or lock one closed, allowing the other to open, said balanced door also acting as a chute.

7. The combination in a car, of a central ⁶⁰ longitudinal member, two sets of doors one on each side of the central member, one door of each set being pivoted to the central member and the other door at the side of the car, two pivoted members arranged to swing over ⁶⁵ the central member so as to form an inverted-V-shaped ridge, or lowered so as to form, with the doors pivoted to the sides of the car, a flat bottom for the car.

8. The combination in a car, of a longitudinal fixed member, two sets of doors, one set on each side of the central member, one door of each set being pivoted to the central member and the other being pivoted at the side of the car, longitudinal ribs at the pivots of ⁷⁰ the said doors arranged to operate the said doors, balanced doors pivoted at a point under the pivots of the first-mentioned doors, and means for turning the first-mentioned doors, members pivoted to each side of the ⁷⁵ fixed member of the car and arranged to rest upon the fixed member to form an inverted-V-shaped projecting rib or to be turned down to form, with the doors pivoted to the side of the car, the flat bottom of the car, substantially as described.

9. In combination, a car having two oppositely-inclined swinging doors, forming a V-shaped hopper, and a balanced door beneath ⁸⁰ said swinging doors for locking said doors in position, substantially as described.

10. In combination, a car having a convertible floor, a depending door hinged to each side of the central longitudinal axis thereof, a door hinged to each side of the car, ⁸⁵ said doors forming a longitudinal hopper at each side of the car with the said depending central doors, and a balanced door for holding said doors in position.

11. In combination, a car having a convertible floor, a depending door hinged to each side of the central longitudinal axis thereof, a door hinged to each side of the car, ⁹⁰ said doors forming with the said depending central doors a longitudinal hopper at each side of the car, and a door for holding said first-mentioned doors in locked position and adapted to form a chute for directing the discharge of the load.

12. In combination, a car having a convertible platform, a depending door hinged to each side of the longitudinal axis thereof, pivoted members adapted to form an inverted-V-shaped ridge, a door hinged at each side of the car, said doors forming a V-shaped ⁹⁵ hopper at each side of the car.

13. In combination, a car having a convertible floor, a rod at each side of the central longitudinal axis thereof, a door hinged to said rod, a rod at each side of the car, a door ¹⁰⁰ hinged to each of said rods, said doors forming a V-shaped hopper, and an inverted-V-shaped partition along the central axis of the car

forming continuous sloping sides with said central depending doors.

14. In combination, a car having a convertible floor, a rod at each side of the central longitudinal axis thereof, a triangular member hinged thereto, a rod at each side of the car, a door hinged to each of said rods, said triangular members and side doors adapted to be converted into a level floor.
15. In combination, a car having a convertible floor, a rod at each side of the central longitudinal axis thereof, a triangular member and a door hinged to each of said rods, a rod at each side of the car, two doors hinged thereto, one of said doors adapted

to be converted into a level floor with one of said triangular members.

16. In combination, a car having two inclined swinging doors forming a longitudinal V-shaped hopper, and a balanced door beneath said swinging doors, substantially as described.

In testimony whereof I have signed my name to this specification in the presence of two subscribing witnesses.

HERBERT L. AULLS.
